UNITED STATES PATENT OFFICE.

THEODORE SCHERF, OF CLEVELAND, OHIO, ASSIGNOR TO THE CLEVELAND-AKRON BAG COMPANY, OF CLEVELAND, OHIO, A CORPORATION OF OHIO.

MULTIPLY PAPER.

1,289,926.

Specification of Letters Patent. Patented Dec. 31, 1918.

Application filed February 21, 1917. Serial No. 150,174.

To all whom it may concern:

Be it known that I, THEODORE SCHERF, a citizen of the United States, residing at Cleveland, in the county of Cuyahoga and State of Ohio, have invented a certain new and useful Improvement in Multiply Paper, of which the following is a full, clear, and exact description, reference being had to the accompanying drawings.

- 10 This invention relates to multi-ply paper and limitedly to paper having incorporated therewith transversely extending threads, the threads serving to reinforce or "web" the paper so as to strengthen the same, making it suitable for the production of bags or similar receptacles for heavy and granulated or finely divided material. In the production of such paper, I arrange the same so that the fibers of certain plies will extend 15 at substantially right angles to the fibers of the other ply or plies, whereby the resultant multi-ply paper will be of substantially uniform strength in all directions. Further and more limited objects to be secured by 20 my invention will appear in connection with the detailed description, and such objects will generally be realized in and through the subject matter of the claims appended hereto.
- 25 In the drawing forming part hereof, Figure 1 represents a perspective view of a sheet of multi-ply paper produced in accordance with my invention, some of the plies being folded back; and Fig. 2 is a longitudinal sectional view through such sheet of multi-ply paper.

30 In producing the paper illustrated herein, I apply, by any suitable mechanism (such as shown in my application Serial No. 40 148,204, filed Feb. 12, 1917) threads (or reinforcing strips) to a web of adhesive-coated paper, the threads or strips running lengthwise of said web and being united to the web through the adhesive material by 45 any suitable mechanism, such as rollers, or belts and rollers. In order to prevent the lateral shifting of these threads or strips, I apply to said threads or strips a ply of paper, which may be of tissue and which may 50 be united to the web and to the threads or strips by means of the adhesive material with which the said web is coated, and this uniting of the two plies of paper and the interposed threads or strips may be accom-

plished by the same mechanism which unites 55 the threads or strips to the web.

On top of the second web, I deposit, in succession and with their adjacent lateral edges in substantial contact, sheets of reinforced paper. Each of these sheets is preferably a compound sheet composed of two plies of paper having interposed therebetween, and united thereto by a suitable adhesive, threads or strips which extend lengthwise of the fibers of such plies, the 60 multi-ply sheets being deposited upon the tissue web with their reinforcing threads or strips extending at right angles to the reinforcing threads or strips on the first web and with the fibers of the plies extending at 65 right angles to the fibers of the web and of the tissue sheet. These sheets are preferably applied to the tissue sheet in advance of the pressing or uniting means and will be united to such tissue sheet by means of 70 adhesive material with which the surface of the tissue web adjacent to said sheets is coated. This uniting of the first two webs and their interposed threads or strips with the sheets may be accomplished in part by 75 the belt and roller arrangement such as shown in my aforesaid application. After passing between the belts, the compound or multi-ply sheet composed of the two webs and the transversely extending sheets is delivered to additional pressing and uniting 80 means located beyond the initial pressing or uniting means (which, as stated, may be belts). In order to provide a smooth and continuous surface or backing for the sheets, 85 I feed to the second pressing or uniting means a web of adhesive-coated paper the fibers whereof extend in the same direction as the fibers of the first two webs, delivering the last mentioned web to the sheets and 90 the first two webs at the second pressing and uniting means whereby the said second pressing or uniting means will incorporate the last mentioned web with the first two webs and with the transversely extending 95 sheets.

The resultant multi-ply paper will be composed of the first mentioned web, the warp threads or strips, the second ply or web of paper (preferably tissue), the transverse sheets of two-ply paper having the fibers thereof extending at right angles to the fibers of the first two webs and having 100

therebetween reinforcing threads or strips extending at right angles to the first mentioned threads or strips, and a final ply of paper composed of a web having its fibers 5 extending in the same direction as the fibers of the first two webs. This paper is particularly strong and is capable of being employed in the production of receptacles, (such as bags) for the shipment of heavy 10 material, as plaster. Reference has been made to the fact that, for the second ply or web, I preferably employ tissue paper. This paper absorbs the paste ordinarily employed for uniting the plies of multi-ply 15 paper and not only retains the warp threads against lateral displacement, but provides a most efficient means for uniting the first web with the transverse sheets. As a means for further insuring a firm adhesive bond between the transverse sheets of two-ply paper and the longitudinal sheet of two-ply 20 paper, the bottom plies of the transverse sheets are preferably composed of tissue paper.

25 In the drawing, the first or foundation web of the paper is indicated at 1; the warp threads or strips for said paper at 2; the web of tissue paper which coöperates with the first web to secure such threads or strips 30 in place at 3; the two plies of the transverse sheets at 4 and 5, respectively; the threads interposed between the last mentioned plies at 6; and the final web at 7.

In applying the sheets to the second web, 35 I may make use of the mechanism shown in my aforesaid application for the purpose of feeding a multi-ply reinforced sheet comprising the webs 4 and 5 and having the threads 6 incorporated therewith and for 40 cutting such sheet into individual sheets the length whereof is substantially equal to the width of the first two webs and for depositing such severed sheets successively upon the second web. For the purpose of applying 45 the final web 7 to the severed sheets which are deposited upon and initially united to the web 3, I may also employ the mechanism shown in the aforesaid application.

Having thus described my invention, 50 what I claim is:

1. A multi-ply sheet of paper comprising a web, spaced reinforcing threads on said web, a sheet of tissue paper applied to said web and said threads and united to said 55 web by adhesive material, and a sheet of reinforced paper applied to the tissue sheet and united thereto by adhesive material.

2. A multi-ply sheet of paper comprising a web, spaced reinforcing threads extending longitudinally of said web, a sheet of tissue 60 paper applied to said web on the side opposite to said threads and united to said

web by adhesive material, and sheets of two-ply paper applied to the tissue sheet and with their fibers extending at substantially 65 right angles to the fibers of the web and tissue sheet and united to the latter sheet by adhesive, there being reinforcing threads between the plies of the two-ply paper extending at substantially right angles to the first 70 mentioned threads.

3. A multi-ply paper comprising a web, spaced reinforcing threads extending longitudinally of said web, a sheet of tissue paper applied to said web and said threads and 75 united by adhesive material to said web, sheets of webbed or reinforced paper extending transversely of the said web and tissue sheet, and united to said tissue sheet by adhesive material, and a web applied to such 80 transverse sheets on the side opposite the first mentioned web and united thereto by adhesive material.

4. A multi-ply sheet of paper comprising a web, reinforcing threads extending longitudinally of said web, a second web applied to said threads opposite the first mentioned web, transverse sheets of paper each having incorporated therewith reinforcing threads extending at right angles to the first mentioned threads, and a web applied to said sheets on the side opposite the first two webs, said webs, sheets, and threads being united 90 by adhesive material.

5. A multi-ply sheet of paper comprising 95 a web, reinforcing threads extending longitudinally of said web, a second web applied to said threads opposite the first mentioned web, transverse sheets of paper each having incorporated therewith reinforcing threads 100 extending at right angles to the first mentioned threads, and a web applied to said sheets on the side opposite the first two webs, said webs, sheets, and threads being united by adhesive material and the fibers 105 of the webs extending substantially at right angles to the fibers of the sheets.

6. A multi-ply sheet of paper comprising a web, reinforcing threads extending longitudinally of said web, a second web applied 110 to said threads on the side opposite the first mentioned web, transversely extending sheets of multi-ply paper having reinforcing threads extending between the plies thereof at right angles to the first mentioned threads, and a web extending in the same direction as the first mentioned webs and applied to said sheets on the side opposite said webs, the said webs, sheets, and threads being united by adhesive material.

In testimony whereof, I hereunto affix my signature.

THEODORE SCHERF.
